UNITED STATES PATENT OFFICE

SALLY BRYAN, OF DENVER, COLORADO

DESIGN FOR A PERFORATED CONTAINER FOR MATERIAL FOR IMPARTING RADIUM EMANATIONS TO FLUIDS

Application filed December 11, 1928. Serial No. 29,213. Term of patent 14 years.

To all whom it may concern:

Be it known that I, SALLY BRYAN, a citizen of the United States, residing in the city and county of Denver, State of Colorado, have invented a new, original, and ornamental Design for a Perforated Container for Material for Imparting Radium Emanations to Fluids, of which the following is a specification, reference being had to the accompanying drawing, forming part hereof.

The figure is an elevation view of a perforated container for material for imparting radium emanations to fluids, showing my new design.

I claim:

The ornamental design for a perforated container for material for imparting radium emanations to fluids, as shown.

SALLY BRYAN.
